UNITED STATES PATENT OFFICE.

DAVID B. WHISTLER, OF DAYTON, OHIO, ASSIGNOR TO THE AMERICAN RAILWAYS EQUIPMENT COMPANY, OF DAYTON, OHIO, A CORPORATION OF OHIO.

COIN AND PAPER-TICKET FARE-BOX.

1,234,705.

Specification of Letters Patent.

Patented July 24, 1917.

Application filed July 11, 1916. Serial No. 108,684.

To all whom it may concern:

Be it known that I, DAVID B. WHISTLER, a citizen of the United States, residing at Dayton, in the county of Montgomery and 5 State of Ohio, have invented certain new and useful Improvements in Combination Coin and Paper-Ticket Fare-Boxes, of which the following is a specification, reference being had therein to the accompanying drawings.

This invention relates to improvements in combination coin and paper ticket registering fare boxes for use on street cars operated on the prepayment system of fare 15 collection, and has for its object to provide a fare box that will meet all requirements, in a single machine, of fare register, fare box and ticket handling device.

The present construction is a modification 20 of the invention which forms the subject matter of my copending application for Letters Patent Serial No. 108,355, filed July 10, 1916; the two inventions being alike in the main objects attained, but differing materially 25 in the construction of the coin and paper ticket receiving and separating mechanism.

The fundamental idea of the invention, as in the case of the earlier application, is to 30 provide a unitary machine upon which all fares may be registered, and through which all money-value fares may be collected and mechanically safeguarded without intermediate handling. To this end the fare box is 35 provided with the usual money counter to register the value of cash fares; also with a trip-passenger counter and a total-passenger counter, the trip-passenger counter indicating at all times registration of the full passenger load, and the total-passenger counter 40 serving as a basis to check operations from one conductor, to another, or from one day to another. Transfers, passes, etc., are collected over the box but are registered on the 45 box the same as coins and tickets paid into the box, the registering mechanism being actuated once for each fare paid of whatever kind.

The combination of fare register and fare 50 box meets every requirement, in a single machine, of the "double check" system of fare collection, without the use of the overhead fare register, as is now common practice, and, therefore, simplifies the work of conductors by having all fares registered on one

machine instead of two. The conductor's attention is not divided between fares paid into the fare box and fares rung-up on the fare register, and the opportunities for "misses" of fares, errors of registration, and other irregularities, whether voluntary or involuntary, which cause much loss to railway companies, are materially reduced.

To be able to collect paper tickets through the fare box with equal facility and with 65 the same safeguards as cash fares is an improvement of great importance in fare collection. It adapts the registering fare box to the regular form of ticket fares, approved by both railway companies and the 70 public and established by long and general usage. The fullest degree of protection is thus obtained as all money-value fares are paid direct into the fare box without intermediate handling, and full collection and 75 full accounting of the fares is assured. This higher development of the fare box, combined with the features of a fare register, makes checking by inspection possible by the same methods as with a fare register. 80 An inspector upon entering a car can check the registrations upon the fare box trip-passenger register against the passenger load and make all other observations in the usual manner, as by observing the number of passengers 85 entering and leaving the car in connection with the registration of fares, he has full check of the situation.

The mechanism employed in the present invention is of simple, durable construction, 90 and in every way well adapted to the purposes intended under the conditions and exigencies of use to which it is to be submitted. The respective groups of the mechanism are connected in such a manner as not to be 95 easily rendered out of adjustment. No intricate or delicate parts are used and ample provision is made in all other respects to insure against breakage. While a preferred form of construction has been used, it is 100 obvious, of course, that various modifications of the mechanism will occur to persons skilled in the art without departing from the spirit of the invention, and I wish it to be understood therefore, that I do not consider 105 the invention limited to the exact construction shown.

In the accompanying drawings Figure 1 is a sectional view of the fare box showing the operating mechanism in elevation. Fig. 110

2 is a sectional view, in elevation, of the mechanism taken on the line $x-x$ of Fig. 3. Fig. 3 is a top plan view of the mechanism with the upper part of the receiving box 5 broken away. Fig. 4 is the stationary member of the coin and ticket separating device, showing the concaved, apertured walls and the ribs which prevent tickets lying upon the bottom of the concaved surface. Fig. 5 is a 10 perspective view of the operable member of the coin and ticket separating device, showing the apertured wall and the teeth on the convexed surface thereof which serve to engage the tickets when same are positioned 15 upon the ribbed wall of the stationary member shown in Fig. 4, and remove them from the separating device. Fig. 6 is a detail plan view of the coin positioning tubes, and the mechanism to discharge the coins from the 20 tubes and to control the registrations upon the total cash counter. Fig. 7 is a detail elevation of the total cash counter and its actuator mechanism which forms part of the 25 group of mechanism shown in Fig. 6. Fig. 8 is a detail perspective view of the coin tubes, and Fig. 9 is a detail view of the shaft assembly carrying the total passenger counter actuator. Figs. 6, 7, 8 and 9 are reduced in size more than the other figures 30 of the drawings.

Referring to the drawings, 1 is the box or case in which the main part of the fare box mechanism is contained; 2 is the top cover of the case, and the base for the fare 35 receiving and examination box 3 which is rectangular in shape, and is formed of cap piece 4 which has an opening 5 through which coin and ticket fares may be paid into the box, and frame members 6 which support glass walls 7 through which fares in box 3 may be visually examined. Within the inclosure formed by case 1 and cover 2 are main frames 8 of the mechanism which are supported in the walls of case 1 by bolts 40 45 9 extending through case 1 from side to side and supported in the walls thereof. In the upper part of the machine, located between frames 8, are two trough-shaped members 10 and 11 which, in their assembled relation as shown in Figs. 1 and 2, form the coin and ticket separating device. Part 10 is rigidly secured to frames 8 and is suspended between the upper walls of the frames in substantially a horizontal plane with the 50 55 trough turned up, so that it constitutes a receptacle or housing to receive fares and is provided with bearings 12 to receive shafts 13 of part 11 which, being of smaller size than part 10, is arranged within the trough of part 10 and also has the trough turned up. Part 10 is further provided with ribs 14 running crosswise of the inner walls of the trough and spaced to form relatively wide channels or grooves, and 60 65 with apertures 15 extending through the

walls thereof. Part 11 is provided with teeth 16 and apertures 17 and with a stud 17^a. When parts 10 and 11 are assembled and have the relation shown in Figs. 1 and 2, the apertures of both parts are in alignment, and the teeth of part 11 project into the grooves formed between the ribs of part 10, for purposes which will presently be described. Rotation of part 10 is accomplished through the train of gears 18, 19, 21, 22, and 23; gear 18 being secured to operating crank 24 by means of stud 25, sleeve 26 and screw 27. Gears 21, 22 and 23 are located on the rear frame 8, gear 21 being connected to gear 19 located on the front frame 8, by 70 75 shaft 28. Gear 23 is secured to the protruding end of inner shaft 13 of part 11, gear 22 being an intermediate between gears 21 and 23 to give the desired direction of rotation to part 11. Gears 21 and 23 are in the ratio of 1 to 4 so that one turn of operating handle 24 will cause one-quarter turn of the fare separating member 11. Also meshing with gear 23 is intermediate gear 32, connected with drive gear 31 which is 80 secured to shaft 30 of fare guard wheel 29 contained within the walls of the fare receiving box 3. The bottom of the receiving box is formed of drop plates 33 secured to and swinging upon shafts 34 which are provided with arms 35 connected with trip arm 36 by means of links 37. Plates 33 are normally held in raised position by springs 38, and the free end of trip arm 36 lies in the path of stud 17^a carried in the end wall of 90 95 part 11.

In the operation of the fare box, crank 24 is given one complete turn for each fare collected, whether the fare is a coin or ticket paid into the box, or a transfer, or pass, etc., collected over the box, the operation is the same, which, through the gear train described, causes the fare separating member 11 to be rotated one-quarter turn and the fare guard wheel one-half turn at each operation of the crank, and causes lug 17^a to contact with trip arm 36 upon every fourth turn of the crank; the trip arm being moved to the left by the further travel of pin 17^a, causes plates 33, through connecting links 110 115 37 and arms 35, to be drawn down to the position indicated in dotted lines in Fig. 1. Fares deposited into the opening 5 are thus positively delivered into receiving box 3 by partial rotation of guard wheel 29, and fall 120 upon plates 33 where they remain, exposed for visual examination through the glass walls of the box, during the interval of four operations of crank 24. When plates 33 are moved to the lowered position, any fares 125 thereon will fall into the trough of separating member 11 which upon each fourth turn of the operating crank will be positioned substantially horizontal between the frames with the trough turned up to receive the 130

fares as they fall from the plates. When part 11 is in the position described, the apertures in parts 10 and 11 are in alinement and, being of suitable size to permit the 5 passing of coins but to prevent the passing of tickets, the coins gravitate therethrough and the tickets are retained in the trough of part 11 until the second and third operations of the crank when the trough will be 10 inverted and the tickets therein will fall into the trough of part 10, and lie suspended above the bottom of the trough upon ribs 14 until the fourth operation of the crank when part 11 will again be moved into the first 15 described relation with part 10 and the tickets will be engaged by teeth 16 and pushed out of trough 10 into the ticket canceling devices. The ticket canceling devices comprise perforating and ink-canceling rolls 20 39 supported upon shafts 40, and operated through gear train 18, 41, 42 and 43. The canceling rolls are supplied with ink from ink roll 44 supported in frame 45. Adjustment of the canceling rolls is provided 25 for by means of set screws 47, and the ink roll is held in contact therewith by tension of spring 46. The tickets after they have passed through the canceling devices are delivered into the ticket storage box C which 30 may be locked to prevent access to the canceled tickets except to authorized persons.

The coins that pass through the apertures of the separating members 10 and 11 are delivered into a rectangular-shaped coin 35 separating device 48, having baffle plates 49 and apertured partition plates 50 and 51, the device resting upon four rocker arms 52, 52', 53 and 53', the arms 52 and 52' being secured to and rocking with shaft 54, and 40 arms 53 and 53' being loosely mounted and rocking upon shaft 55. Movement is imparted to the coin separating device from crank 24 through gears 18 and 41 which has secured to its outer face an eccentric cam 56 45 connected with the upper end of pitman arm 57 by means of rollers 58 secured to the pitman; the lower end of the pitman being secured to arm 59 pinned to shaft 54. Operation of crank 24 causes vibratory movement 50 of the coin separating device 48, and coins falling upon the upper baffle plate 49 will be shaken over the lower edge thereof upon plate 50, the apertures in which are too small to permit nickels, the largest size coin to be 55 handled through the fare box, to pass therethrough, but large enough to permit pennies and dimes and any other coins smaller than a nickel, to pass therethrough and fall upon lower baffle plate 49, from which by 60 the continued rocking motion of the separator, the coins will fall over the edge of the plate upon plate 51 in which the apertures are too small for pennies but large enough for dimes to pass through and fall 65 upon the bottom plate 49^a of the separator,

Nickels are discharged from plate 50 through an opening in the wall of the separator, into coin tube 60, and, in like manner, dimes are discharged from plate 49^a into coin tube 61. Pennies are discharged 70 from plate 51 through an opening in the rear wall of the separator, into coin box B which may be locked to prevent access to the pennies except to authorized persons. The openings in the walls of the coin separating device through which the coins are discharged from the separator are graduated 75 to approximately the thickness of the respective coins to prevent mutilated coins and foreign objects thicker than the coins from 80 passing through the separator into the registering mechanism where breakage of the mechanism might occur by becoming obstructed by the irregular-shaped objects.

The registering mechanism and counter 85 construction shown in Figs. 1, 2, and 3 is substantially the same as that shown and described in my copending application above mentioned and does not form in its detail construction any part of the subject matter of the claims of this application. However, counter mechanism to register the fares as they are paid into the fare box cooperates with the separating devices, and I have, therefore, shown enough of the detail 90 counter mechanism to produce an operative construction. As above explained, every fare is registered on the fare box immediately as collected by means of operating handle 24, which transmits registering 100 movement through gear train 18, 19, 20 which is integral of gear 19, 20^a, 21^a and 22^a to the units wheel of the total passenger counter D; and through gear train 18, 19, 20, 20^a, 23^a, and 24^a to the units wheel of the 105 trip-passenger counter E; one unit being registered upon each of said counters at each turn of handle 24. Coins are registered from tubes 60 and 61 by being removed from the tubes by the lateral movements of the coin discharge arm 62 which is actuated by cylindrical cam 63 secured to shaft 55 which has secured to its outer end gear 19^c, forming part of gear train 18, 19^a, 19^b and 19^c to which movement is imparted 110 from operating crank 24. The arm discharges nickels and dimes from tubes 60 and 61 alternately, the coins as they are removed from the bottom of the tubes contact with the free end of register control arm 65 115 which through connecting arm 66 moves the counter actuator 67 into operative relation with the units wheel of money counter F; operating movement being transmitted to the counter actuator from operating handle 120 24 through gear train 18, 19^a, 19^d and 19^e secured to shaft 68 upon which counter actuator 67 is slidably secured. The actuator has two sets of actuators, of one tooth and two teeth, and the units wheel of the money 125 130

counter F has the figures 0-5 in series of ten upon its periphery so that registration upon the counter will be in units of 5¢; thus when a nickel is discharged from coin tube 5 60 one 5¢-unit will be caused to be registered upon the money counter F, and when a dime is discharged from tube 60, two 5¢-units will be caused to be registered upon the counter. When the registration of a 10 coin is completed, drop plate 69 upon which the coins rest during the registering operation, after the same have been pushed out of the coin tubes, is moved to the position shown in Figs. 1 and 2, and the coins fall 15 into money box A to which the conductor may have access for the purpose of making change. The drop plate is normally held in raised position, closing the discharge opening between the coin tubes, by tension 20 of spring 70, and is moved to the lower position to drop coins from the plate by action of cam 71, in contact with arm 72 which forms an integral part of shaft 73 to which drop plate 69 is secured. 25 The operation of the device will be readily understood from the foregoing description and it will be apparent that I have provided a separator for coin and ticket fares comprising a device in the form of an apertured plate to receive mixed coins and 30 tickets, the apertures of said device being of such a character and so arranged that the coins will pass through the same but the tickets will not pass through the same. Further, the arrangement is such that under 35 ordinary circumstances the coins will pass through the openings by gravity. Coöperating with the apertured plate is a second device which is positively actuated to engage 40 the tickets on the first device and remove the same therefrom. This device is, in the present instance, shown as arranged within the first-mentioned device and adapted to have coins and tickets deposited therein, and 45 is provided with apertures through which the coins may pass, the apertures in the two devices being so arranged that when the movable device is in one position the apertures in the two devices will register. It 50 will be obvious, however, that the movable device may be of any suitable character which will enable it to engage and remove the tickets from the first-mentioned apertured device and that it need not be of the 55 construction here shown. It will further be apparent that the shape of the first-mentioned apertured device may vary from that here shown, and that the number of apertures employed therein will vary according 60 to the shape and character of the separating device, it being only necessary that there should be an opening, or openings, so arranged as to permit the coins to pass through the same. Therefore, while I have 65 shown and described one embodiment of

my invention I wish it to be understood that I do not desire to be limited to the details thereof as various modifications will occur to a person skilled in the art.

Having thus fully described my invention, what I claim as new and desire to secure by Letters Patent is:

1. In a machine of the character described; a separator for mixed coin and ticket fares, a common receiving box for the fares having means to deliver the same into the separator; said separator comprising an apertured, fixed part and an apertured part operable to admit fares from the receiving box to the separator and coacting with said fixed part to cause coins to pass through the apertures in said parts and to remove tickets from the separator; and means to operate said machine. 75

2. In a machine of the character described; a separator for mixed coin and ticket fares, and a common receiving box for the fares having means to deliver the same to the separator; said separator comprising an apertured, fixed part and a part operable to receive fares from said box and coacting with said fixed part to cause the coins to pass through the apertures thereof, and to remove tickets from the separator; and means to operate said machine. 85 90

3. In a machine of the character described; a separator for mixed coin and ticket fares, and means to deliver fares thereto; said separator comprising an apertured, fixed part, and an operable part to receive the fares from said delivering means and coacting with said fixed part to cause coins to pass through the apertures therein, and to remove tickets from the separator; and means to operate said machine. 95 100

4. In a machine of the character described; a separator for mixed coin and ticket fares, and a device having a raised and a lowered position to receive and deliver fares thereto; said separator comprising an apertured, fixed part and an operable part to receive the fares from said device and coacting with said fixed part to cause coins to pass through the apertures therein and to remove tickets from the separator; and means to operate 110 115 said machine.

5. In a machine of the character described; a separator for mixed coin and ticket fares, and an intermittently, operable device to deliver fares thereto; said separator comprising an apertured, fixed part and an operable part to receive the fares from said device and coacting with said fixed part to cause the coins to pass through the apertures therein and to remove tickets from the separator; and means to operate said machine. 120 125

6. In a machine of the character described; a separator for mixed coin and ticket fares, comprising an apertured, fixed part and an apertured, operable part coacting therewith 130

to cause coins to pass through the apertures of said parts and to remove tickets from the separator; and means to operate said machine.

5 7. In a machine of the character described; a separator for mixed coin and ticket fares, comprising an apertured, fixed part and an apertured, rotatable part coacting therewith to cause coins to pass through the apertures 10 of said parts and to remove tickets from the separator; and means to operate said machine.

8. In a machine of the character described; a separator for mixed coin and ticket fares, comprising an apertured, fixed part and a rotatable part coacting therewith to cause coins to pass through the apertures therein and to remove tickets from the separator; and means to operate said machine.

20 9. In a machine of the character described; a separator for mixed coin and ticket fares, comprising an apertured, concaved part and an apertured, convexed part coacting therewith to cause coins to pass through the apertures in said parts and to remove tickets from the separator; and means to operate said machine.

25 10. In a machine of the character described; a separator for mixed coin and ticket fares, comprising an apertured, concaved part and a rotatable, convexed part coacting therewith to cause coins to pass through the apertures therein and to remove tickets from the separator; and means to operate said machine.

30 11. In a machine of the character described; a separator for mixed coin and ticket fares, comprising an apertured, concaved part and an operable, convexed part coacting therewith to cause coins to pass through the apertures therein and to remove tickets from the separator; and means to operate said machine.

45 12. In a machine of the character described; a separator for mixed coin and ticket fares, comprising a fixed part having an apertured, concaved wall and an operable part having an apertured, convexed wall coacting with the wall of said fixed part to cause coins to pass through the apertures 50 in said walls and to remove tickets from the separator; and means to operate said machine.

55 13. In a machine of the character described; a separator for mixed coin and ticket fares, comprising a fixed part having an apertured, concaved wall, and an operable part having a convexed wall coacting with the concaved wall to cause coins to 60 pass through the apertures therein and to remove tickets from the separator; and means to operate said machine.

65 14. In a machine of the character described; a separator for mixed coin and ticket fares, comprising an apertured, con-

caved part and an apertured, convexed part operable within the concavity thereof and coacting therewith to cause coins to pass through the apertures of said parts and to remove tickets from the separator; and means to operate said machine.

70 15. In a machine of the character described; a separator for mixed coin and ticket fares, comprising an apertured, concaved part and a convexed part operable within the concavity thereof and coacting therewith to cause coins to pass through the apertures therein and to remove tickets from the separator; and means to operate said machine.

75 80 16. In a machine of the character described; a separator for mixed coin and ticket fares, comprising an apertured, concaved part and a part operable within the concavity thereof and coacting therewith to cause coins to pass through the apertures therein and to remove tickets from the separator; and means to operate said machine.

85 17. In a machine of the character described; a separator for mixed coin and ticket fares, comprising a fixed, concaved part and an operable, convexed part coacting therewith to separate the coins and tickets; and means to operate said machine.

90 95 18. In a machine of the character described; a separator for mixed coin and ticket fares, comprising a fixed, concaved part and a part operable within the concavity thereof and coacting therewith to separate said fares; and means to operate 100 said machine.

105 110 19. In a machine of the character described; a separator for mixed coin and ticket fares, comprising a fixed, concaved part having an apertured, ribbed wall, and an operable, convexed part having teeth coacting with said ribbed wall to cause coins to pass through the apertures therein and to remove tickets from the separator; and means to operate said machine.

115 120 20. In a machine of the character described; a separator for mixed coin and ticket fares, comprising an apertured, concaved part and an apertured, convexed part having a plurality of positions relative to the first-mentioned part, being adapted in one of said positions to receive the fares and to coact with the fixed part to cause coins to pass through said apertures, and in another of said positions to deliver tickets 125 into the concavity of said fixed part and subsequently to coact therewith to remove said tickets from the separator; and means to operate said machine.

125 130 21. In a machine of the character described; a separator for mixed coin and ticket fares, comprising a fixed, apertured part, and a part having a plurality of positions relative thereto, and adapted in one position to admit fares into the separator

and to coat with said fixed part to cause coins to pass through the apertures therein, and in another position to deliver tickets to said fixed part and subsequently to coat therewith to remove the tickets therefrom; and means to operate said machine.

22. In a machine of the character described; a separator for mixed fares, comprising a fixed part and a part having a plurality of positions relative thereto, and adapted in one position to admit fares to the separator and in another position to coat with the fixed part to separate said fares; and means to operate said machine.

15 23. In a machine of the character described, a separator for coin and ticket fares comprising a concave part having apertures to permit the passage of coins, and a part movable over the concave surface of the 20 first-mentioned part to remove tickets therefrom.

24. In a machine of the character described, a separator for coin and ticket fares comprising a fixed concave part having apertures to permit the passage of coins, and a part movable over the concave surface of 25 said fixed part to remove tickets therefrom.

25. In a machine of the character described, a separator for coin and ticket fares comprising a substantially semicircular part 30 having apertures to permit the passage of coins, and a second part mounted on the axis of said semi-circular part and coöperating therewith to cause tickets to be discharged therefrom.

35 26. In a machine of the character described, a separator for coin and ticket fares comprising a fixed substantially semicircular part having apertures to permit the 40 passage of coins, and a second part rotatable about the axis of said semicircular part and coöperating therewith to cause tickets to be discharged therefrom.

27. In a machine of the character described, a separator for coin and ticket fares 45 comprising two substantially semicircular members mounted on a common axis and of different diameters, said members having apertures to permit the passage of coins, and 50 means for causing one of said members to rotate about said axis independently of the other member.

28. In a machine of the character described; a separator for mixed coin and 55 ticket fares, comprising a part having an apertured, fixed surface, and a part having a movable surface coating with said fixed surface to cause coins to pass through the apertures therein and to remove tickets 60 therefrom; and means to operate said machine.

29. In a machine of the character described; a separator for mixed coin and ticket fares, and a device to deliver fares 65 thereto; said separator comprising a part

having an apertured, fixed surface and a part coating with said device to admit fares into the separator and having a movable surface coating with said fixed surface to cause coins to pass through the apertures therein and to remove tickets therefrom; and means to operate said machine.

30. In a machine of the character described; a separator for mixed coin and ticket fares, and an intermittently, operable 75 device to deliver fares thereto; said separator comprising a part having an apertured, fixed surface, and a part coating with said device to admit said fares into the separator and having a movable surface coating with 80 said fixed surface to cause coins to pass through the apertures therein and to remove tickets therefrom; and means to operate said machine.

31. In a machine of the character described, a separator for mixed coin and ticket fares having an apertured part through which coins may pass and which will intercept tickets, and a rotatable device to remove tickets from said apertured 90 part.

32. In a machine of the character described, a separator for mixed coin and ticket fares having an apertured part through which coins may pass and which will intercept tickets, and a rotatable toothed 95 device to remove tickets from said apertured part.

33. In a machine of the character described, a separator for coin and ticket 100 fares comprising an apertured part arranged to permit coins to pass through the same by gravity and to prevent the passage of tickets, and a positively operated part to engage tickets on the first-mentioned 105 part and remove the same therefrom.

34. In a machine of the character described, a separator for coin and ticket fares, comprising a device having an aperture to permit the passage of coins and so shaped 110 that coins will be directed toward said aperture by gravity, and means to remove the tickets from said part.

35. In a machine of the character described, a separator for mixed coin and 115 ticket fares comprising a housing having an aperture through which coins may pass, and an operable toothed device to remove tickets therefrom.

36. In a machine of the character described, a separator for mixed coin and ticket fares having means to permit coins to pass therefrom by gravity, and a rotatable toothed device to remove tickets therefrom.

37. In a machine of the character described, a separator for fares, having single 125 means to receive mixed coins and tickets, a plurality of means to permit the coins to pass from the separator, and a rotatable toothed device to remove tickets therefrom. 130

38. In a machine of the character described, a separator for mixed coin and ticket fares having an apertured part through which coins may pass and which will intercept tickets, and an operable device having teeth to remove the tickets from said apertured part.
39. In a machine of the character described, a separator for mixed coin and ticket fares, comprising a grooved part having an aperture through which coins may pass, and an operable part coacting with the grooved part to discharge the tickets from the first-mentioned part.
- 15 40. In a machine of the character de-
- scribed, a separator for mixed coin and ticket fares, comprising a part having a plurality of grooves and provided with apertures through which coins may pass, and a plurality of devices coacting with said grooves to discharge tickets from said part.
41. In a machine of the character described, a separator for mixed coin and ticket fares, comprising a housing having a plurality of grooves and provided with apertures through which coins may pass from the housing, and a plurality of teeth extending into said grooves and coacting therewith to remove the tickets from the housing.

DAVID B. WHISTLER.
